UNITED STATES PATENT OFFICE.

ABRAM M. KOLP, OF SALUNGA, PENNSYLVANIA.

BALING-PRESS.

1,122,612.

Specification of Letters Patent. Patented Dec. 29, 1914.

Application filed March 31, 1914. Serial No. 828,563.

To all whom it may concern:

Be it known that I, ABRAM M. KOLP, a citizen of the United States, residing at Salunga, in the county of Lancaster and State of Pennsylvania, have invented a new and useful Baling-Press, of which the following is a specification.

This invention relates to baling presses and more particularly to means for feeding 10 material to the presses.

One of the objects of the invention is to provide, above the press, a condensing chamber into which material may be fed in any preferred manner and where the material will be initially compressed, means being provided for discharging the compressed material from the condensing chamber and into the press box immediately upon the retraction of the follower within the press 20 box.

A further object is to provide condensing means movable with the follower and which operates to reduce the area of the condensing chamber during the retraction of the follower, thus initially compressing the material so that the tamper can be brought into play to direct the compressed material into the press box.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a top plan view of the machine, parts being broken away and the follower being shown at the end of its compression stroke while the compression chamber is shown enlarged to its greatest extent. Fig. 2 is a section on line A—B Fig. 1 and showing, in full lines, the 45 relative positions of the parts illustrated in Fig. 1 and, in dotted lines, the relative positions of the parts during the ejection of the initially compressed material into the press box. Fig. 3 is a section on line C—D 50 Fig. 1. Fig. 4 is a section on line E—F 55

Fig. 1. Fig. 5 is a perspective view of the follower for initially compressing or condensing the material and of the means for connecting the same to the follower in the press box. Fig. 6 is a perspective view of 60 one of the guard plates used within the condensing chamber.

Referring to the figures by characters of reference 1 designates a press box of any suitable size and proportions and provided, at one end, with longitudinally projecting angle strips 2 constituting guides between which a follower 3 is adapted to travel when retracted from the press box. This follower has a pitman 4 connected to it and which 70 may be actuated in any preferred manner.

The press box is provided in its top near one end with a feed opening 5, this opening being closed by the follower 3 at all times except when said follower is approaching 75 its extreme outward position.

Erected upon the press box at the sides of the opening 5 are upwardly diverging side walls 6 of a condensing compartment 7. Each of these side walls is provided at one 80 end with an inwardly extending wall 8 having an outwardly or forwardly extending vertical flange 9 and hung within and between these flanges are bars 10 having their intermediate portions offset to form elongated cranks or hangers as shown particu- 85 larly in Figs. 2 and 4.

Each of the side walls 6 is provided with suitable reinforcing structures such as indicated generally at 11 and secured upon one 90 of these structures and adjacent the ends of the side wall mounted thereon are upstanding brackets 12 between which extends the frame 13 of an endless conveyer 14. This frame 13 bridges the condensing chamber 7 95 and bears downwardly upon both walls 6 thereof, the brackets 12 engaging the frame adjacent the upper edge of one of the walls 6 while the upper edge portion of the other wall 6 is engaged by the depending end member 15 of the frame 13. Thus the upper 100 end portions of the walls are tied together by the frame 13. The end member 15 is held constantly upon the adjacent wall 6 by means of one or more straps 16 which are 105 secured to said end member and to the adjacent reinforcing frame 11. The brackets 12 constitute means for adjustably supporting frame 13, each of these brackets having a longitudinal series of apertures 17 any 110

one of which is adapted to receive a pin 18 which enters the frame 13. Thus angular adjustment of said frame 13 can be effected.

The endless conveyer 14 is mounted on 5 rollers 19 or the like, one of these rollers being provided with a sprocket 20 designed to receive motion, through a chain 21, from a sprocket 22 secured to one end portion of a crank shaft 23. This crank shaft is jour- 10 naled within standards 24 upstanding from the sides of the frame 13 above one side portion of the condensing chamber 7 and any suitable means, not shown, may be provided for actuating the crank shaft 23. This 15 crank shaft is provided with preferably two oppositely disposed cranks 25, as shown in Fig. 2, each crank being pivotally engaged by a toothed feed bar 26 having an upstanding toothed tongue 27 at that end thereof 20 nearest the conveyer 14. The opposite end of each bar 26 is slidably mounted upon the end member 15 of the frame 13 and within an upstanding guide yoke 28 upon said end member. A cushioning spring 29 may be 25 carried by each bar 26 and within the yoke 28. Thus it will be seen that when the shaft 23 is rotated in the direction indicated by the arrow in Fig. 3, the conveyer 14 will be driven in the direction indicated by the arrow 30 in said figure. Consequently any material placed on the conveyer will be fed to position under the upstanding toothed tongues 27 on the bars 26 and will be drawn downwardly by said tongues into the chamber 7 where it will be engaged by the toothed 35 bars 26 and drawn transversely of the chamber 7. The bars 26 will of course be given a combined sliding and circular movement.

For the purpose of initially condensing 40 the material within the chamber 7 prior to its being fed into the press box 1, a follower such as shown in detail in Fig. 5 is employed. This follower includes a head 30 designed to fit snugly between and against the side walls 6, said head having side wings 45 31 designed to bear against said side walls and having a top cutoff plate 32 movable in a path close to the plane occupied by the lower edges of the frame 13.

The head 30 is fixedly connected to arms 50 33 upstanding from coupling bars 34 which are slidably mounted on the press box 1 and within the condensing chamber 7, these bars extending under the inwardly extended wall 55 8 and being connected to the follower 3 by means of brackets 35 secured to the sides of the follower 3. Guard plates 36 are hung from the upper edges of the side walls 6 and are adapted to slide therealong, these guard 60 plates being extended downwardly and over the bars 34 and concealing the wings 31. The said guard plates 36 are substantially equal in width to the inlet opening 5.

By referring particularly to Fig. 2, it 65 will be seen that when the follower 3 is shift-

ed inwardly to its point of greatest compression, the head 30 is shifted longitudinally to a point remote from the opening 5 so that the area of the condensing chamber 7 is thus greatly increased, that portion of the top of 70 the press box between the head 30 and the opening 5 forming the bottom of the condensing chamber and being located directly under the packing bars 26.

A feed arm or tamper 37 is movable down- 75 wardly into the condensing chamber 7 and is mounted in any suitable manner, this arm being actuated in any manner desired. For example, and as shown in the drawings, a weight 38 may be suspended from the pivot 80 end of the arm and may be fixedly connected to the arm, this weight projecting into the path of the follower 3 so that, when the follower approaches the outer limit of its movement, it will strike against the weight and 85 thus cause the tamper 37 to swing downwardly into the condensing chamber 7. When, however, the follower 3 is projected into the press box, the weight 38 will elevate the tamper 37 to its initial position. It is of 90 course to be understood that any other means can be employed for actuating the tamper 37 and said tamper can be of any other construction than that illustrated.

When shaft 23 is actuated the conveyer 95 14 will direct material to the understanding 100 tongue 27 and said tongue will be actuated in the manner herein described so as to pack the said material downwardly within the condensing chamber where it will be shifted 105 transversely of the chamber by the toothed bars 26, this operation of compression taking place directly above that portion of the top of the press box located in front of the head 30 and above the closed opening 5, as shown 110 in Fig. 2.

The mechanism provided for actuating the follower 3 is so timed relative to the packing and feeding mechanism that, when a predetermined amount of material has 115 been condensed within the chamber 7, the follower 3 will be retracted from under the opening 5 and, during the movement of this follower the head 30, through its connecting bars 34 and brackets 35 will be 120 drawn longitudinally along the top of the press box, thus reducing the area of the condensing chamber 7 and initially compressing the material directly above the opening 5. During the completion of the 125 outward stroke of the follower 3, the feeding finger or tamper 37 will be actuated so as to move downwardly into the condensing chamber and force the initially compressed material through the opening 5 and into the path of the follower 3. During the return or compression stroke of the follower, this material will be pushed forward into the press box while the head 30 will also 130 be pushed forward, thus enlarging the

area of the compression chamber 7 whereupon a further supply of material can be condensed in the manner hereinbefore set forth. While the head 30 is in its forward or compressing position, the plate 32 assumes a position under the packing bars and tongues 26 and 27, thus preventing additional material being fed by the conveyer 14 into the chamber 7. When, however, the head 30 is moved back to the position shown by full lines in Fig. 2, any material which may have been deposited onto the plate 32 and in engagement with the packing bars 26 and tongues 27, will be directed downwardly into the enlarged condensing chamber.

The bars 10 hereinbefore described and which form hangers extending between walls 8, will swing outwardly under the action of the compressed material within the compression chamber 7, thus to relieve the walls 8 of excessive pressure.

The guard plates 36 will travel with the head 32 and its wings 31 and prevent material from being packed downwardly between the arms or bars 34 and the side walls 6.

As before pointed out, the conveyer 14 can be adjusted angularly so as to extend either horizontally or at an incline.

30 What is claimed is:—

1. The combination with a press box having an inlet in the top thereof, and a follower adapted to close the inlet during its forward movement and to open the inlet during its outward movement, of upwardly diverging walls secured upon the press box at opposite sides of the inlet, a head slidably mounted between said walls and upon the press box, wings upon the head and engaging said walls, bars fixedly connected to the head and movably mounted upon the top of the press box, connections between said bars and the follower whereby the head and follower are caused to move together, and bails connecting the side walls at one end and in the path of the head, said head and bails coöperating to condense material placed between the walls during the outward movement of the follower.
2. The combination with a press box having an inlet in the top thereof, and a follower adapted to close the inlet during its forward movement and to open the inlet,

during its outward movement, of upwardly diverging walls secured upon the press box 55 at opposite sides of the inlet, a head slidably mounted between said walls and upon the press box, wings upon the head and engaging said walls, bars fixedly connected to the head and movably mounted upon the 60 top of the press box, connections between said bars and the follower whereby the head and follower are caused to move together, bails connecting the side walls at one end and in the path of the head, said 65 head and bails coöperating to condense material placed between the walls during the outward movement of the follower, means extending across the space between the upstanding walls, the bails, and the head for 70 feeding material to said space during the inward movement of the follower, and means carried by the head for cutting off the supply of material during the outward movement of the head and the condensing 75 of the material in the path of the head.

3. The combination with a press box having an inlet in the top thereof and a follower mounted for reciprocation within the box, of upwardly extending side walls 80 fixedly mounted on the press box at opposite sides of the inlet, a connection between said walls at one end, a head mounted to slide between and extending up to the walls, said head, walls and connection forming a 85 condensing chamber, bars fixedly connected to the head and slidable on the press box, connections between the bars and the follower, said head and the connections between the walls coöperating to condense material 90 within the chamber during the outward movement of the follower, means extending transversely across the condensing chamber for feeding material into the condensing chamber, and means upon the head for 95 passing under the feeding means to cut off the supply of material to the condensing chamber during the compression of the material therein by the head.

In testimony that I claim the foregoing 100 as my own, I have hereto affixed my signature in the presence of two witnesses.
